CHAIR HAVING VERTICALLY ADJUSTABLE FOOTREST

Filed April 22, 1948

UNITED STATES PATENT OFFICE

2,546,871

CHAIR HAVING VERTICALLY ADJUSTABLE FOOTREST

Laura Walker Schley, Miami, Fla.

Application April 22, 1948, Serial No. 22,691

1 Claim. (Cl. 155—172)

1

The present invention relates to a novel and improved chair which is provided with practical and efficient adjustment facilities whereby the one chair may be used to advantage by both children and adults.

It is a matter of common knowledge that babies may be accustomed to using high chairs and also small chairs in the toy category. When, however, they begin to grow, there becomes a stage of development in which neither high chairs nor small chairs are suitable for their needs and purposes, particularly while eating from the conventional type tables. Many makeshift provisions are therefore adopted, such as sitting on pillows, on books and the like. To say the least, these makeshift methods are wholly unsafe and impractical.

With the foregoing difficulties in mind, I have evolved and produced a chair which includes not only adjustable legs but a complementary adjustable foot rest, the two together serving the average needs and requirements of growing children.

More specifically, in carrying out the principles desired, I utilize extensible and retractable auxiliary legs for adjustment purposes and these are fitted telescopically into main tubular legs.

Another phase of the invention has to do with a special frame which is suspended from the bottom of a chair said frame serving as an adapter for a vertically adjustable foot rest or step.

Other features and advantages will become more readily apparent from the following description and the accompanying illustrative drawings.

In the drawings, wherein like numerals are employed to designate like parts throughout the same:

Figure 1 is a perspective view of a kitchen or equivalent chair constructed in accordance with the principles of the present invention;

Figure 2 is an enlarged sectional view which may be said to be taken approximately on the vertical line 2—2 of Figure 1, looking in the direction of the arrows;

Figure 3 is a fragmentary sectional and elevational view showing one of the extensible legs;

Figure 4 is a perspective view of a bracket;

Figure 5 is a perspective view of one of the leg frames; and

Figure 6 is a perspective view of the foot rest adapter frame.

Referring now to the drawings by distinguishing reference numerals, it will be seen that the leg frames, which are of U-shaped tubular forms used in so-called metal chairs, are denoted by the numerals 8 and 9 and these are duplicates

2

and the bight portions 10 (see Fig. 2) are suitably screwed or otherwise fastened to the under side of the cushioned bottom 11. The back rest is denoted by the numeral 12 and is of suitable construction and attached to the chair bottom as shown. The legs proper which are vertical are denoted by the numerals 13 and they are provided with vertically spaced and aligned bolt holes 14 to accommodate the screw-threaded portion 15 (see Fig. 3) of a thumb bolt 16. The bolt is placed in selected bolt holes and has a stud 17 on its inner end to fit into a stud hole provided in the tubular extensible and retractile leg 18. This is a small tubular member, as shown in Figure 3, and has a suitable foot 19 screwed into place, as at 20. By extending and retracting the auxiliary legs, the height of the chair bottom may be regulated to the plane desired and to accommodate different sizes of growing children.

20 The foot rest adapter frame is denoted by the numeral 21 in Figure 6. This comprises a tubular rectangular frame, the mid portion 22 of which is bolted to the under side of the chair bottom as shown in Figure 2.

25 The vertical limb portions are denoted by the numerals 23, and like the chair legs are provided with bolt holes to accommodate studs on thumb bolts 24, which thumb bolts are carried by sleeves 25, the sleeves being slidable on said limbs as shown in Figure 2. The sleeves carry triangular brackets 26 which in turn serve as supports for the step or foot rest 27. There is a cross brace or strut 28 forming the remaining part of the adapter frame and this has its end portions suitably attached between the front legs 13 of the chair as shown better in Figure 1.

30 Novelty is predicated upon the extensible and retractile telescoping sleeves 18 which constitute adjustment legs and which are provided with detachable feet and are adjustably bolted in the regular tubular legs 13. Further novelty is predicated upon chair legs with adjustable feet in conjunction with a foot rest on the front legs, which foot rest is adjustable to coincide with the adjustment made in reference to the legs. More specific novelty is predicated upon the construction of the foot rest, the brackets and the adapter frame means 21 which is employed to accommodate the foot rest.

35 In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claim.

Having described the invention, what is claimed as new is:

A chair of the class described comprising a horizontal bottom having a vertical back rest, a pair of duplicate spaced parallel vertically disposed U-shaped leg frames having their bight portions attached to the underside of said bottom, said leg frames providing front and rear legs, a third U-shaped frame, smaller than the first-named U-shaped frames, said third frame having its bight portion attached to the underside of the forward edge portion of said bottom and its limb portions depending in spaced parallelism between the respective front legs of the first-named leg frames, a horizontal cross brace connected to the lower ends of the limbs of said third U-shaped frame, said cross brace being connected

at its opposite ends to the lower portions of said front legs, and a foot rest slidably mounted on the vertical limbs of said third U-shaped frame.

LAURA WALKER SCHLEY.
